UNITED STATES PATENT OFFICE.

JOHN TEVIS HEARN, OF VICTORY, GEORGIA.

OVERSHOE-FASTENER.

No. 897,287.

Specification of Letters Patent.

Patented Sept. 1, 1908.

Application filed November 4, 1907. Serial No. 400,613.

To all whom it may concern:

Be it known that I, JOHN TEVIS HEARN, a citizen of the United States, residing at Victory, in the county of Carroll and State of Georgia; have invented certain new and useful Improvements in Overshoe-Fasteners, of which the following is a specification.

This invention relates to overshoes and more particularly to fasteners therefor, and 10 has for its object to provide an overshoe equipped with strings by means of which it may be quickly and securely attached to the foot.

Another object is to provide a novel arrangement of strings in connection with the shoe.

Other objects and advantages will be apparent from the following description and it will be understood that changes in the specific 20 structure shown and described may be made within the scope of the claims without departing from the spirit of the invention.

In the drawings forming a portion of this specification, and in which like numerals of 25 reference indicate similar parts in the several views, Figure 1 is a view showing a human foot wearing the present shoe, Fig. 2 is a top plan partly in section showing the arrangement of the strings, Fig. 3 is a section taken 30 vertically across the forward part of the shoe illustrating the transverse portions of the strings.

Referring now to the drawings, there is shown an overshoe 5 having a pair of openings 6 in each side adjacent to the heel. These 35 openings are provided with eyelets as shown, and are spaced to each other longitudinally of the shoe. A pair of similar openings 7 are formed in the shoe just forwardly of the open 40 portion of the shoe and at each side thereof. These openings 7 are also spaced from each other longitudinally of the shoe and the forward opening 7 is dropped slightly below the rearward opening, as indicated at 7'.

45 A string 8 is provided for each side of the shoe, these strings being engaged through the openings 6 and tied around the portions of the shoe between these openings 6. The strings are then brought forwardly outwardly 50 of the shoe, each string thus consisting of two end portions 8^a and 8^b respectively.

The end portions 8^b of the strings are engaged through the forward openings 7, these end portions being carried across the interior

of the shoe, as shown. The end portions 8^a 55 of the strings are similarly engaged through the rearward openings 7 and the extremities of the end portions of the strings are brought upwardly over the forward portion of the shoe to be tied together. With this arrangement, the strings extend transversely within the forward portion of the shoe, as described, to rest upon the forward portion of the foot. It will thus be seen that when the free extremities of the strings are pulled to 60 tighten the strings, the rearward portion of the shoe will be drawn forwardly to tightly engage the heel of the wearer, and the transverse strands within the shoe at the forward portion thereof will be drawn tight against 65 the forward portion of the foot. Furthermore, the portions of the strings extending over the outer face of the forward portion of the shoe will tightly engage the latter to aid in holding the shoe in position. 70

What is claimed is:

1. An overshoe having a pair of openings spaced from each other longitudinally of the shoe at each side of the shoe adjacent to the heel, the forward opening of each pair being 80 located slightly below the rearward opening of each pair, said shoe having also a pair of openings forwardly of the opening of the shoe and each side thereof, the corresponding openings of the two pairs being in registration with each other transversely of the shoe, the forward opening of each pair being located slightly below the rearward opening of the corresponding pair. 75

2. The combination with an overshoe having spaced openings in each side adjacent to its heel, said shoe having a pair of spaced openings therein at each side in its forward portion, of a string tied in each pair of the rearward openings, said strings having their end 90 portions brought forwardly exteriorly and passed through the forward openings of the shoe to extend transversely of the shoe therewithin, said strings having their extremities brought upwardly exteriorly of and 95 over the forward portion of the shoe and fastened together. 100

In testimony whereof I affix my signature, in presence of two witnesses.

JOHN TEVIS HEARN.
